UNITED STATES PATENT OFFICE.

SAMUEL G. GOSS, OF GLENCOE, ILLINOIS, ASSIGNOR TO THE GOSS PRINTING PRESS COMPANY, OF CHICAGO, ILLINOIS, A CORPORATION OF ILLINOIS.

PLATE-BENDING MACHINE.

1,126,982.

Specification of Letters Patent.

Patented Feb. 2, 1915.

Application filed May 29, 1913. Serial No. 770,575.

To all whom it may concern:

Be it known that I, SAMUEL G. Goss, a citizen of the United States, residing at Glencoe, in the county of Cook and State of Illinois, have invented certain new and useful Improvements in Plate-Bending Machines, of which the following is a specification, reference being had to the accompanying drawings.

My invention relates to machines for bending plates into circular form and is intended more particularly for use in bending electrotype-plates used on printing presses, although it may be used for any other purpose for which it is adapted.

Heretofore it has been customary to bend such plates by placing them on a thick sheet of rubber, or equivalent support, and passing them between rollers set a predetermined distance apart so that the rollers act to press the plate into the rubber and thereby cause it to curve to conform to the curvature of the upper roller. While in such machines one of the rollers has been adjustable toward and from the other by suitable adjusting screws, such adjustability has been provided merely for the purpose of varying the extent to which pressure is applied to the plates operated upon.

Machines of this character are objectionable because it is difficult to introduce the plate and rubber support into the bite of the rollers owing to their being set so close together, and moreover, in such machines, owing to the flexibility of the rubber, the plate is very apt to be moved out of proper alinement, and consequently is not bent to a true curvature.

I avoid the objections incident to such machines by providing a machine in which the curving or bending roller is movable, so that when not in use it is held far enough from the table on which the rubber sheet rests to permit the leading end of the plate to be positioned under it freely, after which the roller is moved down into position to exert the desired pressure upon the plate. The plate is then moved under the roller, all parts of it receiving the same pressure, and consequently the bending is properly accomplished. After the plate has been bent, the roller is again moved away from the support to receive the next plate, these operations being automatically performed as the machine operates.

In the accompanying drawings, which illustrate one embodiment of my invention,—Figure 1 is a side elevation of my improved bending machine; Fig. 2 is a longitudinal vertical section on line 2—2 of Fig. 3; and Fig. 3 is a vertical cross-section on line 3—3 of Fig. 1.

Referring to the drawings,—4 indicates a support, which is preferably mounted on suitable legs or standards 5, so that the support is held at the desired height. The support 4 is provided with a longitudinal slot 6, as shown in Fig. 2.

7 indicates a table, which is mounted on the support 4 and is movable longitudinally thereof, said table resting on anti-friction rollers 8, carried by the support 4, as shown in Figs. 1 and 2. The table 7 is of suitable size to receive the electrotype plate and is provided with a downwardly-extending tongue 9, which projects through the slot 6, and properly guides the table 7 as it reciprocates.

10 indicates an arm, which projects downwardly from the tongue 9, and is in the form of a channel-bar, being provided with marginal flanges 11—12, best shown in Fig. 2.

13 indicates a shaft which is arranged transversely under the support 4 and is provided with a crank 14, having a roller 15, which lies in the channel of the arm 10, so that the roller 15 is adapted to engage one or the other of the flanges 11—12. As best shown in Fig. 2, the flanges 11—12 are spaced apart a considerably greater distance than the diameter of the roller 15, so that there is considerable lost motion as the crank 14 rotates, the purpose of which is to allow the table 7 to remain stationary while the movement of the bending roller is effected, as hereinafter described. The shaft 13 is driven by means of a worm gear 16 mounted thereon, and meshing with a worm 17, carried by a shaft 18, best shown in Fig. 1. The latter shaft is driven from an electric motor 19, or other suitable source of power, through gears 20—21, also shown in Fig. 1.

22 indicates the rubber sheet or pad upon which the electrotype-plate 23 rests while being bent.

24 indicates a swinging gage, carried by a bracket 25, secured to the forward edge of the table 7. The gage 24 is prevented from

dropping below a horizontal position by a lug 26, best shown in Fig. 2. The purpose of the gage 24 is to facilitate the alinement of the front edge plate with the axis of the bending roller when it is placed upon the pad 22.

27 indicates the bending roller, which extends transversely of the table 7, and is mounted upon an eccentric or crank-shaft 10, journaled in suitable standards 29, secured at opposite sides of the support 4. The roller 27 rotates freely upon the crank-shaft and may be moved toward or from the table 7 with its axis in parallelism therewith by turning the crank-shaft or eccentric in its bearings.

30 indicates a lever carried by the crank-shaft 28 and keyed thereto, so that by swinging said lever, the crank-shaft may be rocked.

31 indicates a bellcrank-lever fulcrumed upon a suitable pivot 32, shown in a dotted line in Fig. 1, 33—34 indicating the two arms of said bellcrank lever. The arm 33 is connected with the lever 30 by a connecting rod 35, so that by rocking said bellcrank-lever the lever 30 may be operated to rock the crank-shaft 28 and move the roller 27 toward or from the table 7.

30 36 indicates a cam-groove on one face, preferably the inner face, of the worm-gear 16. The shape of the cam-groove 36 is shown in Fig. 1, in which the heavy dotted lines indicate one position of said cam-

35 groove, and the light dotted lines indicate a different position thereof. The arm 34 of the bellcrank-lever 31 is provided with a roller 37, which runs in the cam-groove 36. The shape of the cam 36 is such that as the 40 gear 16 rotates it rocks the bellcrank-lever 31 in the manner hereinafter described to move the bending roller 27 up or down, as required, and also holds said roller in position during the bending operation.

45 The operation of the machine is as follows: The plate to be bent is placed face down on the pad 22 and its leading edge is placed under the bending roller 27 which then occupies the position shown in full 50 lines in Fig. 1. The gear 16 rotates in the direction indicated by the arrow in Fig. 1, and the rotation of said gear, through the cam 36, operates to move the bellcrank-lever 31 into the position shown in dotted lines in

55 Fig. 1, bringing the arm 33 thereof into line with the connecting-rod 35. This not only rocks the crank-shaft 28 to move the bending roller down into operative position, but also locks the roller in such position by reason of 60 the fact that the arm 33 is substantially in alinement with the connecting-rod 35. Preferably, the lower pivot 38 of the connecting-rod 35 moves slightly across a line connecting the fulcrum 32 and the upper pivot 39

65 of the connecting-rod 35, thus making a

more secure lock. During this part of the operation the roller 15 swings idly across the arm 10 from the flange 11 to the flange 12, so that the table 7 is not moved. As soon as the bending roller 27 has been moved down to operative position, the roller 15 engages the flange 12 and moves the table 7 longitudinally of the support 4, thus carrying the plate 23 under the bending roller. The cam 36 is so shaped that it does not move the bellcrank-lever during this part of the operation. As soon as the plate has passed from under the bending roller, at which time the roller 15 will start to move back across the arm 10 toward the flange 11, the cam operates upon the bellcrank-lever 31 to move the bending roller upward, thereby permitting the table 7 to be moved back to its original position as soon as the roller 15 again engages the flange 11. The plate in bending follows up around the bending roller and may be removed as soon as it is free from the grip of such roller.

While I have shown my invention embodied in a machine employing a traveling table for supporting the plate, in its broader aspect it contemplates any other suitable means for supporting the plate and causing it to move under the bending roller. The claims hereinafter made are, therefore, generic in character and are to be construed accordingly.

That which I claim as my invention, and desire to secure by Letters Patent, is,—

1. In a plate-bending machine, the combination of bending members comprising a substantially flat plate-support and a bending roller adapted to roll upon a plate carried by said support to bend the same around said roller, one of said bending members being movable toward and from the other to vary the width of the passage between them, means for moving said plate-support transversely with relation to the axis of said bending roller to cause said roller to roll over the plate, and means for automatically moving said bending members closer together at the beginning of the bending operation to reduce the width of the passage between them.

2. In a plate-bending machine, the combination of bending members comprising a substantially flat plate-support and a bending roller adapted to roll upon a plate carried by said support to bend the same around said roller, one of said bending members being movable toward and from the other to vary the width of the passage between them, means for moving said plate-support transversely with relation to the axis of said bending roller to cause said roller to roll over the plate, and means associated with said moving means for automatically moving said bending members closer together at the beginning of the bending operation to

reduce the width of the passage between them.

3. In a plate-bending machine, the combination of bending members comprising a substantially flat plate-support and a bending roller adapted to roll upon a plate carried by said support to bend the same around said roller, one of said bending members being movable toward and from the other to vary the width of the passage between them, means for moving said plate-support transversely with relation to the axis of said bending roller to cause said roller to roll over the plate, and means for automatically moving said bending members closer together at the beginning of the bending operation to reduce the width of the passage between them, and for moving them farther apart after the plate has been bent.

4. In a plate-bending machine, the combination of bending members comprising a plate-support adapted to travel in a substantially horizontal plane and a bending roller adapted to roll upon a plate carried by said support to bend the same around said roller, one of said bending members being movable toward and from the other to vary the width of the passage between them, means for moving said plate-support transversely with relation to the axis of said bending roller to cause said roller to roll over the plate, and means associated with said moving means for moving said bending members closer together at the beginning of the bending operation to reduce the width of the passage between them.

5. In a plate-bending machine, the combination of bending members comprising a plate-support adapted to travel in a substantially horizontal plane and a bending roller adapted to roll upon a plate carried by said support to bend the same around said roller, one of said bending members being movable toward and from the other to vary the width of the passage between them, means for moving said plate-support transversely with relation to the axis of said bending roller to cause said roller to roll over the plate, and means associated with said moving means for moving said bending members closer together at the beginning of the bending operation to reduce the width of the passage between them, and for moving them farther apart after the plate has been bent.

6. In a plate-bending machine, the combination of bending members comprising a substantially flat plate-support and a bending roller adapted to roll upon a plate carried by said support to bend the same around said roller, said roller being movable toward and from said support to vary the width of the passage between them, said plate-support being movable transversely with relation to the axis of said bending

roller, and operating mechanism operatively connected with said plate-support and with said roller and acting first to move said roller toward said plate-support to reduce the width of the passage between them and then to move said support transversely of the axis of said roller.

7. In a plate-bending machine, the combination of bending members comprising a substantially flat plate-support and a bending roller adapted to roll upon a plate carried by said support to bend the same around said roller, said roller being movable toward and from said support to vary the width of the passage between them, said plate-support being movable transversely with relation to the axis of said bending roller, and operating mechanism operatively connected with said plate-support and with said roller and acting first to move said roller toward said plate-support to reduce the width of the passage between them, then to move said support transversely of the axis of said roller, and then to move said roller away from said support.

8. A plate-bending machine of the type described, comprising a reciprocating support adapted to receive the plate to be bent, a vertically-movable bending roller coöperating with said support to press the plate between them, mechanism for reciprocating said support, and means operated by said reciprocating mechanism for moving said roller down into operative position before the support is moved in one direction by said reciprocating mechanism, for maintaining said roller in its operative position while said support is moved in one direction, and for moving said bending roller up out of operative position before the said support is moved in the opposite direction.

9. A plate-bending machine of the type described, comprising a reciprocating support adapted to support the plate to be bent, a shaft, means carried by said shaft for reciprocating said support, a vertically-movable bending roller coöperating with said support to press the plate between them, and means operated by the rotation of said shaft for moving said roller vertically, and for moving said support transversely of the axis of said bending roller while said bending roller is held against vertical movement.

10. A plate-bending machine of the type described, comprising a plate-support, a bending roller coöperating with said support to press between them the plate to be bent, said roller and support being separable for the introduction of the plate between them, and operating mechanism comprising means for automatically moving the bending roller into operative position while the plate is stationary, then moving the plate support under the bending roller while the roller remains in operative position, and

then moving the bending roller out of operative position.

11. A plate-bending machine, comprising a support adapted to receive the plate to be bent and to reciprocate in a substantially horizontal plane, a vertically-movable bending roller adapted to bear upon and roll over the surface of a plate carried by said support, a shaft, means operated by said shaft for intermittently reciprocating said support, and means operated by said shaft for moving said roller vertically while the support is stationary.

12. A plate-bending machine, comprising a support adapted to receive the plate to be bent and to reciprocate in a substantially horizontal plane, a vertically-movable bending roller adapted to bear upon and roll over the surface of a plate carried by said support, a shaft, means operated by said shaft for intermittently reciprocating said support, a cam carried by said shaft, and means operated by said cam for moving said roller vertically.

13. A plate-bending machine, comprising a support adapted to receive the plate to be bent and to reciprocate in a substantially horizontal plane, a vertically-movable bending roller adapted to bear upon and roll over the surface of the plate carried by said support, a crank-shaft on which said roller is mounted, means for reciprocating said support, and means associated with said reciprocating means for rocking said crank-shaft to vary the distance between said roller and said support.

14. A plate-bending machine of the type described, comprising a reciprocating support, means for intermittently reciprocating said support, a bending roller co-operating with said support to press between them the plate to be bent, a crank-shaft on which said roller is mounted, and means operated by said reciprocating means for rocking

said shaft while said support is stationary, to vary the distance between said roller and said support.

15. A plate-bending machine, comprising a reciprocating support adapted to receive the plate to be bent, said support having a channeled arm, a shaft having a crank engaging said channeled arm for reciprocating said support intermittently, a bending roller, a crank-shaft on which said roller is mounted, a cam mounted on said first-mentioned shaft, and means operated by said cam for rocking said crank-shaft to vary the distance between said bending roller and the support.

16. A plate-bending machine, comprising a reciprocating support adapted to receive the plate to be bent, said support having a channeled arm, a shaft having a crank engaging said channeled arm for reciprocating said support intermittently, a bending roller, a crank-shaft on which said roller is mounted, a cam mounted on said first-mentioned shaft, and a bellcrank-lever acted on by said cam and connected with said crank-shaft for rocking said crank-shaft to move the bending roller toward and from the support.

17. A plate-bending machine, comprising a reciprocating support adapted to receive the plate to be bent, a shaft, means operated by said shaft for intermittently reciprocating said support, a cam mounted on said shaft, a bellcrank-lever operated by said cam, a bending roller, a crank-shaft on which said roller is mounted, and means connecting said bellcrank-lever with said crank-shaft, said cam being arranged to rock said bellcrank-lever while said plate support is stationary.
